ROTARY INTAGLIO-PRINTING MACHINE.

1,078,219.

Specification of Letters Patent.

Patented Nov. 11, 1913.

Application filed December 24, 1910. Serial No. 599,109.

To all whom it may concern:

Be it known that we, DAVID J. SCOTT and WALTER C. SCOTT, citizens of the United States, and residents of Plainfield, in the county of Union and State of New Jersey, have invented certain new and useful Improvements in Rotary Intaglio-Printing Machines, of which the following is a specification.

10 Intaglio printing is used extensively in printing wall paper and calico, and for this purpose engraved copper cylinders are employed. These cylinders print only on a continuous web. When it is desired to print sheets, the hand method is usually employed.

20 The main object of this invention is to make photogravure printing possible on a large and commercial scale, such as for art and newspaper supplement work, and to enable sheets to be printed, which can then afterward be printed again in different colors in perfect register with the photogravure.

25 Other objects will appear as the specification proceeds.

30 The invention consists of the hereinafter described features of construction, combination of parts and arrangement of elements.

35 In the accompanying drawings the invention is embodied in a concrete and preferred form, but changes may of course be made without departing from the legitimate and intended scope of the claims.

40 In the said drawings: Figure 1 is a general side elevation of a machine embodying the invention. Fig. 2 is an enlarged detail view principally of the form cylinder, inking and wiping mechanisms.

45 Similar characters indicate corresponding parts in the different views.

1 is the feedboard, 2 the impression cylinder, 3 the form cylinder and 4 the delivery mechanism.

50 5 is the inking mechanism, 6 the wiping mechanism and 7 the auxiliary wiping mechanism.

55 Adjacent to the feedboard are located the usual front gages 8. The impression cylinder is provided with an impression surface 9, adjacent to which are suitable sheet taking devices such as the grippers 10. These grippers, as well as the usual overlay tightening

device 11, are located in the two gaps 12 which bound the impression surface 9. A suitable tripping mechanism 13 is provided whereby the impression cylinder can be tripped with reference to the plate cylinder, and suitable means, as the screws 14, are employed to vary the pressure of the impression cylinder against the plate cylinder.

The plate cylinder is preferably located in front of the impression cylinder and the delivery mechanism is preferably located in front of impression cylinder and underneath the plate cylinder. The plate cylinder is provided with two gaps 15 (only one of which is shown) which bound the plate surface of the cylinder in a manner similar to the gaps 12 bounding the impression surface of the impression cylinder. The remainder of the surface of the plate cylinder is preferably turned down below the pitch circumference of the cylinder in a well known manner. In the gaps 15 are located the pivoted clamps 16 which hold the ends of the intaglio plate 17. The tension under which the plate is held can be varied by means of the adjustable screw 18. It will be noticed that the end 19 of the intaglio plate 17 where it is held by the clamp 16 is bent inward below the surface of the cylinder, and that the top of the clamp 16 is also preferably below the surface of the cylinder.

70 The inking mechanism consists, in this instance, of the ink trough or fountain 20, fountain roller 21, ductor roller 22, and distributing roller 23. These rollers are driven positively by means of the pinion 24 meshing with the gear on the plate cylinder. The ductor roller 22 is preferably always in contact with the fountain roller 21 and is pivoted on a center co-axial with the center of rotation of the fountain roller by means of the arms 25. It is caused to vibrate into and out of contact with the plate on the plate cylinder by means of the cams 26, connections 27 and gab hook 28. Said gab hook engages a pin 29 carried by the arm 25 of the ductor roller, and this arm also carries a sector 30 engaging with a corresponding sector 31 mounted on the shaft 32 which extends to the other side of the machine and operates the arm 25 on that side. The cams 26 are adjustable circumferentially with respect to each other by means of the slots 33.

and bolts 34 so as to vary the length of time the ductor roller is in contact with the plate 17 and thus varying the supply of ink. The parts are so timed, however, that the ductor 5 roller will supply ink to the plate 17 only, and not on the blank space of the plate cylinder.

The wiping mechanism consists, in this instance, of a blade 35 set at an angle to the 10 plate cylinder, which blade is supported in the pivoted holder 36. The blade is held up against the cylinder by means of the springs 37 acting through the arms 38. The amount of this pressure is regulated by means of 15 the threaded screws 39. The blade is preferably moved away from the cylinder by means of the cam 40 acting on the cam lever 41. The cam lever 41 has an arm 42 adjustable by means of the screw 43 which 20 contacts with the stop lever 44 of the blade holder 36. This causes the blade to come in contact with the printing plate and to be raised off the blank portion of the cylinder. The screw 43 controls the amount of pressure 25 of the blade against the cylinder. The angle of the blade in relation to the plate on the cylinder is determined by moving the slide 45, which carries holder 36, by means of screw 46. The blade need not, however, 30 be moved toward and away from the cylinder.

The holder 36 and blade carried thereby is vibrated longitudinally of the axis of the cylinder by means of the cam 47, pivoted 35 lever 48, and socket 49. The amount of vibration is adjusted by changing the point of pivotal support of the lever 48, there being three pivot points shown at 50, 51 and 52.

40 The blade 35 is, in the actual operation of the press, set very accurately to give the best effect according to the work being printed. When it is lifted off the end 19 of the printing plate, it is found to leave 45 a small deposit of ink thereon, which, being added to at each revolution of the press, gathers and tends to fly off, smutting the sheets, etc. To prevent the accumulation of this ink, we provide the auxiliary wiping 50 blade 53, mounted in the auxiliary blade holder 54 carried on the rockshaft 55. On one end of this rockshaft 55 is the cam lever 56 which reaches to the cam 57. This cam is mounted on a shaft making one revolution 55 for each revolution of the plate cylinder and the cam 57 is shaped to cause the auxiliary wiping blade 53 to remain out of contact with the printing plate except at the moment the tail end 19 of the printing plate 60 is passing when the auxiliary wiping blade 53 is caused to give the plate a short quick wipe, thus preventing the accumulation of an excessive amount of ink on the edge of the plate. The surplus ink is gathered in 65 the pan 58.

The various parts such as ink fountains, fountain rollers, ductor roller, doctor blade, auxiliary blade, drip pan, etc., are all preferably easily accessible and quickly removable.

The sheets being printed are fed from the feedboard to the feed gages and are taken as usual in sheet feed machines by the grippers in impression cylinder. After printing, the sheet is transferred in chains 59 which pass over sprockets 60 and 61. The diameter of the sprockets 60 being preferably equal to the impression cylinder, the shaft in which the sprockets are mounted is geared to make the same number of revolutions as the plate and impression cylinder. 75

The chains 59 are provided with grippers 62 which deposit the sheet with the printed side up in front of the impression cylinder and underneath the plate cylinder on the 85 delivery board 63. The grippers 62 are opened by suitable cams.

The impression cylinder 2 is preferably mounted in sliding box 64 sliding in the ways 65 of the frame. The springs 66 normally tend to move the impression cylinder away from the plate cylinder. Mounted in the box 64 is a rockshaft 67 carrying the lever 68 connected to the tripping device 13. 69 is a cap, closing the ways 65, provided with a sliding member 70. Interposed between this sliding member 70 and rockshaft 67 is a link 71 forming with lever 68 a toggle. The screw 14 is tapped into cap 69 and adjusts the sliding member 70. 100

What is claimed, is:

1. In a rotary intaglio printing machine, a form cylinder, an intaglio plate on said cylinder extending over a distance less than the entire surface of the cylinder, means for supplying ink to said plate, means for wiping said plate after inking the same, and an auxiliary wiping mechanism for wiping the tail end of the plate only. 105

2. In a rotary intaglio printing machine, a form cylinder, an intaglio plate on said cylinder extending over a distance less than the entire surface of the cylinder, means for clamping said plate onto the cylinder located below the surface of the same, causing the tail end of the plate to extend below the surface, means for applying ink to said plate, means for wiping that part of the plate which is on the circumference of the cylinder, and an auxiliary wiping mechanism for wiping the depressed tail end of the plate only. 110

3. A printing machine comprising: an impression cylinder, a plate cylinder located in front of the impression cylinder and somewhat higher than the latter, a delivery mechanism arranged in front of the impression cylinder and below the latter and underneath the plate cylinder, an inking apparatus for the plate cylinder disposed 115 125 130

- below the plate cylinder, above the delivery mechanism and in front of the impression cylinder, a wiping mechanism for the plate cylinder located in front of the latter and 5 above the inking apparatus, and an auxiliary wiping mechanism for the plate cylinder located below the latter, above the delivery mechanism and between the impression cylinder and inking apparatus.
- 10 4. A sheet fed rotary intaglio printing machine comprising: an impression cylinder making one revolution to each impression, a plate cylinder also making one revolution to each impression, an intaglio plate 15 covering a portion of the plate cylinder only, inking means for inking the plate after each impression, means for moving said inking means toward and away from the plate cylinder once to each revolution so as not 20 to contact that portion of the plate cylinder not occupied by the plate, means for wiping the plate after each inking and before the next impression, and means for moving said wiping means toward and away from the plate cylinder once to each revolution so as not 25 to contact that portion of the plate cylinder not occupied by the plate.
5. A sheet fed rotary intaglio printing machine comprising: a plate cylinder making one revolution to each impression, an intaglio printing plate covering a portion 30 of the plate cylinder only, inking means for inking the plate after each impression, means for moving the said inking means toward and away from the plate cylinder once to each revolution so as not to contact that portion of the cylinder not occupied by the plate, a doctor blade for wiping the plate after each inking and before the next im- 35 pression, means for moving said doctor blade toward and away from the plate cylinder once to each revolution so as not to contact with that portion of the plate cylinder not occupied by the plate, and an im- 40 pression cylinder coacting with the plate cylinder.
6. In an intaglio printing machine, the combination of a plate cylinder, an intaglio plate thereon, a doctor blade, a pivoted holder supporting said blade, means for 50 rocking said pivoted holder, means for varying the pressure of the blade against the plate, means for varying the angle of the blade in relation to the plate, and means for 55 vibrating the holder longitudinally of the axis of the cylinder.
7. In an intaglio printing machine, the combination of a plate cylinder, an intaglio plate thereon, a doctor blade, a pivoted holder supporting said blade, a spring for 60 forcing the support in one direction around its pivot so as to cause the blade to engage the plate, a cam and adjustable connections to the holder for moving the latter around its pivot away from the cylinder and for 65 varying the pressure of the doctor blade against the plate, and means for varying the angle of the blade in relation to the plate.
8. In an intaglio printing machine, the combination of a plate cylinder, an intaglio plate 70 thereon, a doctor blade, a pivoted holder supporting said blade, a spring for forcing the support in one direction around its pivot so as to cause the blade to engage the plate, a cam and adjustable connections 75 to the holder for moving the latter around its pivot away from the cylinder and for varying the pressure of the doctor blade against the plate, means for varying the angle of the blade in relation to the plate, 80 and means for vibrating the holder longitudinally of the axis of the cylinder.

Signed at Plainfield, in the county of Union and State of New Jersey, this sixteenth day of December, A. D. 1910.
